UNITED STATES PATENT OFFICE.

LOUIS H. LEHMAN, OF PHILADELPHIA, PENNSYLVANIA.

SHOWER INCLOSURE.

Application filed January 18, 1926. Serial No. 81,901.

The object of this invention is to devise a novel shower inclosure, which, when in use, co-operates with the tub in such a manner that the water from the shower will be received within the tub, and which, when not in use, can be moved out of the way.

With the above and other objects in view as will hereinafter appear, my invention comprehends a novel shower inclosure.

10 It further comprehends novel means for supporting and for locking a door or doors in the different positions which such door or doors assume.

15 It further comprehends novel means for sealing the glass in its frame.

Other novel features of construction and advantage will hereinafter more clearly appear in the detailed description and the appended claims.

20 Referring to the drawings:—

Figure 1 is a side elevation of a bath room showing a tub and a shower, and a shower inclosure embodying my invention, in conjunction therewith.

25 Figure 2 is a top plan view of the construction shown in Figure 1.

Figure 3 is a plan view of a locking and supporting mechanism for the door.

Figure 4 is a side elevation of the construction shown in Figure 3.

Figure 5 is a sectional plan view of another locking mechanism embodying my invention.

Figure 6 is a partial section on line 6—6 of Figure 5.

Figure 7 is a side elevation, partly broken away, of Figure 1.

Figure 8 is a bottom plan view of a portion of the door frame seen in Figure 1.

40 Figure 9 is a top plan view of a portion of the bottom bracket seen in Figure 1.

Figure 10 is a sectional view on an enlarged scale of the bottom locking mechanism seen in Figure 1.

45 Similar numerals of reference indicate corresponding parts.

Referring to the drawings:—

1 designates a bath tub of any desired or conventional type, which is located in proximity to the wall 2, from which extends the shower 3.

4 designates a shower inclosure, embodying my invention which comprises a frame 5 which is preferably made of channel bars

of non-corrosive material or of material 55 which has been treated or coated to render it non-corrosive.

The frame 5, as shown in Figures 1 and 2, is formed of a front channel bar 6 and a channel bar 7 which forms top, side and bottom 60 members of the frame.

The side frame members are connected with a bar 8, which serves as a grasping handle and also as a towel bar.

9 is the glass which is secured to the frame 65 in any desired manner, and, preferably, in which the channel of the frame receives a U-shaped packing and sealing strip of flexible material, such as, for example, rubber or cork.

The frame members are connected together in any desired manner, for example by spot welding, rivets or screws. The shower inclosure 4 is rotatably mounted in the upper and lower brackets 11 and 79 respectively. 75 One flange of a bracket 11 is secured to the wall 2 in any desired manner, and the other flange extends transversely from the wall. The transversely extending flange of the lower bracket is positioned slightly above or in 80 proximity to the top of the outer wall of the bath tub 1.

A link 75 has its forward end pivotally connected to the door frame at 76, and at its rear end it is provided with a longitudinally extending slot 77 into which extends a pin 78 fixed to the top bracket 11. The bracket 11 near its free end is provided at its top face with the upwardly extending stud 88, see Figure 7, which is adapted to seat in the recess 85 89 in the bottom of the link 75 when the door is in longitudinal alignment with the outer wall of the bath tub so that when in this position the link is locked. The walls of the recess are preferably rounded, so that, when the door is swung transversely of the top, the link can be moved out of engagement with the stud 88.

The lower bracket 79 is best seen in Figs. 8, 9 and 10. In Figures 1, 8 and 10, the bottom member of the channel bar 7 carries a longitudinally extending locking rib 80 having a threaded aperture 81 opening through it. The rib 80 is wedge shape in cross section and is adapted to seat in the recesses 82 and 83 in the top face of the bracket 79. 84 105 is an aperture through the bracket 79, adapted to receive a screw 85 which passes through

the bracket 79 and is in threaded engagement with the aperture 81. The bottom of the bracket 79 is recessed to receive the head of the set screw 85, and between such head and the bracket is interposed a bent spring 86. When the screw 85 is tightened the spring 86 contributes with the weight of the door to cause the locking rib 80 to be seated in the groove 82 or 83 with which it has been brought 10 into register. When the door is moved into inoperative position it assumes the position shown in dotted lines in Figure 2.

In Figures 3 and 4, I have shown another embodiment of bracket 87. Each bracket 87 is provided at its free ends with a head 12 having a curved or circular portion 13, which is provided with spaced recesses 14 and with the shoulders 15, each of which, if desired, may be provided with the cushion 16, such as, 20 for example, a spring or a piece of rubber secured thereto in any desired manner, for example, by being retained in a recess in such shoulders.

The frame of the door has fixed to it a casing 17, which carries a pintle 18 which extends into the frame and into a recess 19 in the head 12. The casing 17 has its bottom extending to guide the pintle, and contains a plunger 20, and a spring 21, which tends to move the plunger outwardly. The head of the plunger is preferably rounded to adapt it to move more readily into and out of recesses 14. The casing is chambered to receive the spring and its plunger, and a closure 22 covers 35 the chambered portion of the casing, as will be clearly understood from Figure 4.

In this embodiment of my invention seen in Figures 2, 3 and 4, the shower inclosure can be swung into the position seen in full lines 40 in Figure 2, in which it is in alignment with the outer side of the tub, or it can be swung into the position seen in dotted lines in Figure 2, in which it is parallel with the wall.

It can be swung outwardly from the tub, 45 also.

For the purpose of rigidity, both the top and bottom brackets preferably have a locking head 12, and the door frame at the top and bottom has connected with it a casing 17 which carries a locking plunger 20 and a spring 21.

The bottom of the door, near its free end, is preferably provided with a support 23 which may be resilient cushions. In this embodiment, when it is desired to use the bath tub as a bath tub, the shower inclosure can be swung out of the way, so that the faucets 24 can be actuated in the usual manner.

The shower 3 is controlled by the usual and 60 conventional type of valve. In the embodiment seen in Figures 5 and 6, I have illustrated a different form of locking mechanism embodying my invention, in which the bracket which is the equivalent of the 65 bracket 79 is provided with a head 24 having

an internal chamber 25, having in its wall, recesses 26 which are spaced ninety degrees apart.

The frame member 7 is provided with a pintle 27 in the form of a post having a transversely extending aperture 28 therethrough, in which is contained a spring 29, which tends to move outwardly the balls 30 so that they will interlock in diametrically opposed apertures 26 and retain the shower in the position into which it has been moved. The pintle 27 is secured to the door by means of a fastening device 31, which secures in position a cap 32, which covers the top of the pintle 27. In the embodiment seen in Figure 7, I have shown another manner of mounting the upper end of the shower inclosure, in which the top bracket 33 is in the form of an angle, which is secured to the wall, and which is provided with a laterally extending flange which carries a pin 34 which extends into an aperture 35 in the frame of the shower inclosure. 75 80 85

The locking mechanism and door mounting at the bottom of Figure 7 is the same as that hereinbefore described in connection with Figures 1, 2, 8, 9 and 10. 90

Special attention is called to the fact that in my present invention the brackets serve to space the door from the wall a sufficient distance to give the necessary clearance for the valves and to render the valves accessible when the door is transversely of the tub. The pin and slot connection of the upper link serve to limit the movement of the door so that when the door is moved from its longitudinal position to its transverse position it can not pass in the same direction beyond its transverse position. 95 100 105

Having thus described my invention, what I claim as new and desire to secure by Letters Patent, is:—

1. The combination with a bath tub and a shower, of a shower inclosure comprising a door, an upper and a lower supporting bracket therefor, a link pivotally connected with the upper bracket and with the door and locking mechanism co-operating with the lower bracket and the bottom of the door. 110

2. The combination with a bath tub and a shower, of a shower inclosure comprising a door, an upper and a lower supporting bracket therefor, a link pivotally connected with the upper bracket and with the door and locking mechanism co-operating with the lower bracket and the bottom of the door, said locking mechanism being constructed to lock the door in longitudinal alignment with the tub or in a position transversely of the tub. 115 120

3. A shower bath shield comprising a door, an upper and a lower supporting bracket, a link pivoted to the top of the door and having a pin and slot connection with the upper bracket and means co-operating with said lower bracket and the door to retain the door 125 130

in a position longitudinal of or transversely of the tub.

4. A shower inclosure arranged for use with a bath tub having one end thereof abutting against a wall, said inclosure comprising a door and means to pivotally support said door to provide a clearance between the door and said wall when the door is arranged transversely of the tub and to substantially close said clearance when the door is arranged longitudinally of the tub.

5. A shower bath inclosure comprising supporting brackets having curved corners, a shield having curved corners to come into close proximity to the curved corners of said brackets, and said shield and brackets having pivots spaced from said corners.

6. The combination with a bath tub and a shower, of a shower inclosure comprising a door, and brackets carried by a wall against which one end of said tub abuts and to which the door is hinged at a sufficient distance from the wall to render the valves for controlling said shower accessible.

25 7. A shower inclosure arranged for use with a bath tub having one end thereof abutting against a wall, said inclosure comprising a door, and vertically spaced brackets carried by said wall for pivotally supporting said door whereby the latter may be swung

from a position which is longitudinal with respect to said tub to one which is transverse with respect thereto.

8. A shower inclosure arranged for use with a bath tub having one end thereof abutting against a wall, said inclosure comprising a door, and a pair of vertically spaced brackets carried by said wall for supporting said door for pivotal movement about a vertical axis, said brackets being respectively provided with extensions overlying the top and bottom edges of said door such that said vertical axis is arranged between the side edges of said door.

9. A shower inclosure arranged for use with a bath tub having one end thereof abutting against a wall, said inclosure comprising a door arranged to be swung into inoperative position paralleling said wall or into operative position extending perpendicularly with respect thereto, and a pair of brackets carried by said wall for supporting said door, said brackets being pivotally secured to said door at points spaced inwardly from the rear edge thereof such that when the door is swung into said inoperative position a space is provided between it and said wall and when swung into said operative position said rear edge of the door lies against said wall.

LOUIS H. LEHMAN.
